Attorney.*

UNITED STATES PATENT OFFICE.

ANDREW PROUDFOOT COATES, OF SUSSEX, NEW BRUNSWICK, CANADA.

MUSIC TURNER.

Application filed October 31, 1928, Serial No. 316,221, and in Canada November 22, 1928.

- The invention relates to improvements in music turners as described in the present specification and shown in the accompanying drawings which form part of the same.
- 5 The invention has for its object the provision of a device for facilitating the turning of the leaves of a book of music in order that a player of a musical instrument need not stop in the midst of rendering a selection 10 in order to turn over a page. A distinctive feature of this invention is that it is provided with a double control, one for hand operation and the other for foot operation, either of which may be used at the option 15 of the player.
- The invention consists substantially of a box or casing for supporting a music book or the like, clips being provided to hold the book open. At the back is a post which 20 carries an adjustable rod having a clip for the purpose of attaching to the page to be turned. The post is rotatably mounted and has an arm at its lower end that is spring-urged for rotating the post. A detent serves 25 to lock the arm against its spring pressure until the page is to be turned. A lever is connected to the detent in order to withdraw it from engagement with the arm, which lever is located exteriorly of the box or casing. 30 One end of the lever is connected to a keyboard mechanism for manual operation, while the other end of this lever is connected to a foot release mechanism.
- Referring to the drawings, Figure 1 is a 35 perspective view of the invention in its adaptation for use with a piano.
- Figure 2 is a vertical elevation of the mechanism for turning the leaves. This mechanism is mounted upon a backboard 40 that is removably attached to the box or casing.
- Figure 3 is a vertical section taken on the line 3—3 of Figure 2. In this view the arms of the posts are shown in section.
- 45 Figure 4 is a horizontal sectional view taken on the line 4—4 of Figure 2 showing more particularly the release mechanism.
- Figure 5 is a vertical section taken on the line 5—5 of Figure 2.
- 50 Figure 6 is a vertical section taken through one of the keys of the key-box for manual operation.
- Like numerals of reference indicate corresponding part in each of the figures 55 throughout the drawings.
- The invention in its preferred form is shown with a pair of posts for turning two leaves of a book of music and it is to be understood in practice the music turner can be constructed to turn a larger number of 60 leaves if so desired.
- 10 designates the box or casing for housing the mechanism which turns the leaves. Said box or casing preferably has a sloping top 11 and a rest 12 against which the book 65 is placed, which book is shown in outline at 13. The book is held open by clips such as those shown at 14 which clamp it against the rest 12.
- As the mechanism for turning each leaf is 70 of identical construction, a description of one will suffice for both. 15 is a vertical post journalled in bearings 16, which bearings are supported on an upright member 17 that rises from a back-board 18 that is removably attached to the casing 10. The bearings 16 serve to support both posts which are located one behind the other as best seen from an inspection of Figures 1 and 3. The post 15 is of hollow or tubular 75 construction at its top in order to receive a rod 19 that is telescopically mounted therein and secured by a set screw 20. This rod is bent at right angles to the post and carries a clip 21 which in the present instance is of 80 the type commonly used for clipping papers and embodies a pair of spring jaws. This clip is rigidly secured to the rod 19 such as by means of the set-screw 22. This clip is 85 for the purpose of attachment to a leaf of 90 the book that is to be turned.
- The adjustable rod is provided in order to accommodate books of varying heights, it being merely necessary to loosen the set-screw and lower or raise the rod in order to 95 adjust it to books of different heights, the set-screw being tightened when the correct height is reached.
- The lower end of the post 15 has an arm 23 extending therefrom, which arm is rigidly 100 secured thereto and has an upturned distal end 24 upon which is swiveled a plate 25 that attaches to a tension spring 26 of the coil type. The other end of the spring is attached to the back-board 18 as at 27 preferably by means of a set-screw 28 or other equivalent means whereby its tension may be 105 adjusted. One of the posts extends slightly above the other in order that the arms will not interfere with each other in swinging. 110

The spring 26 functions to turn the post and in this manner turns the leaf that is attached to the clip 21. The post is held set or locked by means of the detent 29 until the page is desired to be turned. This detent projects over the upturned portion of the arm 23 in order to restrain it and is retained in this position by a spring 29', the distal end 29' being beveled to click into engagement with the part 24 of the arm. The detent is slidably mounted in bearings 30. The other end of the detent has an eye 31, see particularly Figure 4, in which is fitted an upturned end 32 of a rocker 33. The rocker is mounted in a bearing 34 that also serves to hold the companion rocker which actuates the trip of the mechanism for turning the other page. This bearing 34 is supported upon an extension 35 that is rigidly attached to the back-board 18. The rocker protrudes through an opening in the front 36 of the box or casing and has attached to it a lever 37. The point of attachment is preferably adjacent to the top end of the lever. It will be manifest that upon having set or locked the post by means of the detent 29 it can be released at any time for purposes of turning the page by merely slightly turning the lever 37 in the proper direction. Upon release of the post the spring 26 pulls it around in a semi-circle, and since the leaf is attached to it by means of the clip 21 it is thus turned.

The manual control for the operation of the lever 37 consists of a key box 38 which preferably has a sloping top 39 and a removable back and bottom joined together in the form of an L plate which may be attached to the piano or other instrument in any convenient manner such as by fitting fastening elements in the apertures 40. The front of the box is preferably made slidable in order that access may be had to the mechanism therein contained. A flexible element 42 is attached to the lower end of the lever 37 and extends to the key box 38 and passes therein being secured to a peg 43 about which it is wound in order to keep it taut.

Depending from the top 39 is a pair of spaced guides 44 through which the flexible element 42 is threaded and intermediate of these guides is a key 45 which slidably rises from the top and has its lower end receiving the flexible element. The key is normally held raised by means of a tension spring 46 so that by simply depressing this key it will cause the portion of the flexible element lying between the two guides 44 to sag or deflect thus pulling on the lever 37 which in turn withdraws the detent 29 from engagement with the arm 23 of the posts.

The foot control for the lever 37 consists of a flexible element 47 attached to the upper end of such lever and attached to a vertical rocker 48 at its upper end, the con-

nection being preferably made by means of a peg 49 about which the flexible element may be wound for purposes of maintaining it taut.

The rocker 48 is connected intermediate of its length to a bracket 50 by means of a pivotal pin 51 which bracket is attached in any conventional manner to an end of the piano and also serves to carry the companion rocker arm of the foot control for the other page. The lower end of the lever has a flexible element 52 similarly attached and passed over a pulley 53 of a bracket 54 secured to the piano at a point in the vicinity of the player. The flexible element 52 depends from the pulley 53 and is permanently attached to a pedal generally indicated by the numeral 55, which pedal comprises a curved spring 56 for attachment to the piano in the vicinity of the player's feet and a toe-piece 57 presenting a depressible pad. The page is turned by the foot control by simply depressing the member 57 by means of the foot which pulls upon the flexible element 52 and rocks the rocker 48 causing it to pull upon the flexible element 47 and thus moving the lever 37 in the required direction for releasing the detent 29.

What I claim is:

1. A music turner comprising a casing or box, a rest rising therefrom against which an open music book is placed, spring clips adapted to clamp the book against the rest, a vertical post rotatably supported by the casing or box and located at the back of the book, a rigid member extending radially from the post, means carried by said member for attachment to a leaf of the book, an arm fixedly secured to the post, a spring adapted to rotate said arm, and control means for restraining the arm against its spring pressure.

2. A music turner comprising a supporting element, a post journaled therein, a rigid member extending radially from said post, means carried by said member for attachment to a leaf of a music book, an arm fixedly secured to the post, a spring adapted to rotate said arm, a detent slidably supported and having one end disposed to engage said arm to restrain it against its spring pressure, a rocker engaged with the other end of said detent, a lever fixedly secured to the rocker, a flexible element stretched from said lever to a stationary object, and a depressible key adapted to deflect the flexible element to actuate said lever.

3. A music turner comprising a supporting element, a post journaled therein, a rigid member extending radially from said post, means carried by said member for attachment to a leaf of a music book, an arm fixedly secured to the post, a spring adapted to rotate said arm, a detent slidably supported and having one end disposed to en-

gage said arm to restrain it against its spring pressure, a rocker engaged with the other end of said detent, a lever fixedly secured to the rocker, a finger control for said lever, said control consisting of a key box, a peg rotatable therein, a flexible element attached to the lever at one end and wound about the peg at the other end, guides contained in the key box, a key slidably projecting through the key box, the interior end of the key being connected to the flexible element, and a spring holding the key normally raised.

4. A music turner comprising a supporting element, a post journalled therein, a rigid member extending radially from said post, means carried by said member for attachment to a leaf of a music book, an arm

fixedly secured to the post, a spring adapted to rotate said arm, a detent slidably supported and having one end disposed to engage said arm to restrain it against its spring pressure, a rocker engaged with the other end of said detent, a lever fixedly secured to the rocker, a pedal control for said lever, said control consisting of a flexible element attached to one end to the lever, a rocker attached at one side of its pivot to said flexible element, a flexible element attached to the rocker at the other side of its pivot and trained over a pulley, and a spring held pedal attached to the latter flexible element.

Signed at Sussex, N. B., Canada, the 19th day of October, 1928.

ANDREW PROUDFOOT COATES.
